J. KENNEDY.
EXPANSION ANCHOR.
APPLICATION FILED OCT. 10, 1918.

1,320,623.

Patented Nov. 4, 1919.

UNITED STATES PATENT OFFICE.

JOSEPH KENNEDY, OF RICHMOND HILL, NEW YORK, ASSIGNOR TO J. EDWARD OGDEN,
OF MOUNTAINVILLE, NEW YORK.

EXPANSION-ANCHOR.

1,320,623.

Specification of Letters Patent.

Patented Nov. 4, 1919.

Original application filed June 16, 1917, Serial No. 175,058. Divided and this application filed October 10, 1918. Serial No. 257,541.

To all whom it may concern:

Be it known that I, JOSEPH KENNEDY, a citizen of the United States of America, and a resident of Richmond Hill, Queens county, 5 and State of New York, have invented certain new and useful Improvements in Expansion-Anchors, of which the following is a specification, reference being had to the accompanying drawings, forming a part 10 thereof.

My invention relates to expansion anchors for bolts and its object is to provide a simple and inexpensive structure by means of which bolts may be securely fastened to material of such character that their threads will not satisfactorily engage therewith. More specifically, its object is to provide a structure which under longitudinal pressure will collapse longitudinally along 15 determined transverse lines to thereby expand outwardly against the wall of a hole in which it is placed and contract inwardly against the bolt it is designed to hold.

This application is divided from a co-pending application for patent Serial No. 175,058 filed June 16, 1917, and relates specifically to the type of anchorage disclosed therein, in which the anchorage structure is weakened along longitudinal lines in order 20 to facilitate its collapse in operation.

In order that my invention may be thoroughly understood I will now proceed to describe the same in the following specification, and then point out the novel features 25 thereof in appended claims.

Referring to the drawings:

Figure 1 is a sectional longitudinal elevation of an expansion anchor made according to and embodying my invention shown 30 inserted in a hole before expansion and with a bolt in position.

Fig. 2 is a similar view of the same parts in the positions they assume after expansion.

Fig. 3 is an elevation of the anchor shown 35 in the preceding figures.

Fig. 4 is an elevation of an anchor of modified construction which also embodies this invention.

Fig. 5 is an elevation of a bolt with the 40 anchorage member of Fig. 4 shown in section, and illustrates the way in which this form of the device is used.

Fig. 6 is a sectional longitudinal elevation of an expansion anchor of a modified form

of construction, showing a bolt inserted 55 therein.

Like characters of reference designate corresponding parts in all the figures.

10 designates a bolt; 11 is a metallic tube surrounding this bolt. The tube has an internal diameter slightly larger than the diameter of the bolt. At the inner end of the tube threads 12 are rolled into tube in such a way as to reduce the diameter of the tube 60 at this part and of such size and pitch as to fit the threads of the bolt. The collapsing of the tube is facilitated by providing longitudinal weakenings such as the slots 36. These are shown extending completely 65 through the walls and for a greater part of 70 the length of the anchor, a structure of this kind being readily formed from sheet metal in a well known manner.

The anchor may be made in more than one piece as shown in Fig. 4, in this case of two 75 similar pieces 37 and 38. Such parts may be stamped readily from sheet metal.

Before describing specifically the structure illustrated in the other figures of the drawings, I will point out the manner in 80 which this device is used. A hole is drilled in a wall 15, for example, of sufficient depth and diameter to receive the tube as shown in Fig. 1. 16 is an object which is to be fastened to the wall. The bolt 10 is passed 85 through the object and through the tube into the threads 12. Tightening the bolt will put longitudinal pressure upon the tube which will collapse under this pressure along lines predetermined by the creases 13 90 and 14. This will increase the crimps in the metal which will thus have a tendency to fold up like an accordion. The inward displacement of the metal at the lines 13 is of course limited by the shank of the bolt, and this limitation will assist in forcing the metal of the tube at the lines 14 into the wall 95 of the hole. Thus a firm anchorage with the wall is formed and at the same time that tube is crushed in against the bolt so that the latter has no clearance and is incapable of lateral movement which might in time loosen the anchorage. The parts will have assumed some such positions as those illustrated in Fig. 2.

In the structure shown in Fig. 6, the tube 11^A is made of thicker metal. It is constructed with a clearance hole 20 for the

bolt 10. Its inner end is of smaller diameter and is provided with cast or cut threads 21. At spaced intervals grooves 22 are cut transversely through the inner surface of the bore 20. Between these grooves others designated 23 are cut in the outer surface. These grooves 22 and 23 are of sufficient depth, dependent upon the kind of metal of which the tube is made to insure its 10 buckling in and out when subjected to longitudinal pressure produced by turning the bolt in the threads 21.

The parts 37 and 38 of Figs. 4 and 5 are transversely corrugated. When these are 15 used they are placed over the shank 30 of a bolt, between its head 31 and the object 16 which is moved toward the bolt head 31 by the nut 32.

I intend no limitations other than those 20 imposed by the appended claims.

What I claim is:

1. A bolt anchor comprising a member having longitudinally separated parts, each provided with means for causing said member when subjected to longitudinal pressure, to be crimped onto a bolt and against the wall of a hole in which it is inserted.

2. A bolt anchor comprising a member having longitudinally separated parts each 30 provided with spaced laterally contracted and expanded portions and adapted when subjected to longitudinal pressure to be crimped onto a bolt and against the wall of a hole in which it is inserted.

3. A bolt anchor comprising a tubular member having a slotted portion through a part of its length adapted to collapse longitudinally and expand inwardly and outwardly when subjected to longitudinal 40 pressure.

4. A bolt anchor comprising a tubular member having a longitudinal slotted portion provided with transverse corrugations and adapted to collapse longitudinally and

expand inwardly and outwardly when subjected to longitudinal pressure.

5. A bolt anchor comprising a tubular member having a longitudinally slotted portion provided with equally spaced means thereon for causing said slotted portion to become crimped at equally spaced transverse lines when subjected to longitudinal pressure.

6. A bolt anchor comprising a tubular member provided near one end with threads 55 adapted to receive the threads of a bolt inserted through the tube, said member having a longitudinally slotted portion, and means for causing said member when subjected to longitudinal pressure to be crimped 60 onto the bolt and against the walls of a hole in which it is inserted.

7. A bolt anchor comprising a tubular member provided near one end with threads 65 adapted to receive the threads of a bolt inserted through the tube, said member having a longitudinally slotted portion provided with equally spaced means thereon for causing said slotted portion to become crimped at equally spaced transverse lines 70 when subjected to longitudinal pressure.

8. A bolt anchor comprising a tubular member provided with transverse corrugations and having parts of its wall cut away to collapse longitudinally and to extend 75 radially inwardly and outwardly when subjected to longitudinal pressure.

9. A bolt anchor comprising a tubular member having parts of its wall cut away and provided with equally spaced means for 80 causing such cut away portion of the wall to become crimped on equally spaced transverse lines when subjected to longitudinal pressure.

In witness whereof, I have hereunto set 85 my hand this 7th day of October, 1918.

JOSEPH KENNEDY.
